ABSTRACT OF THE DISCLOSURE

A rotating mirror prism within a cylindrical drum with an opening for allowing radiation from the outside to strike the prism. One edge of the opening extends at an oblique angle to the generatrix lines of the drum to prevent the air current produced by the rotation of the prism from striking all points on the edge simultaneously, thereby reducing the noise caused by the air current striking the edge.

BACKGROUND OF THE INVENTION

The invention relates to a device for damping acoustic vibrations caused by the rotation of a prismatic body within a cylindrical drum which is arranged concentrically with the rotational axis of the prismatic body and the wall of which is provided with at least one opening arranged so that the sides of the prismatic body pass by this opening in turn when the body rotates.

A prismatic body rotating within a drum is used for instance in the optical system of such cameras for photographing with infrared light which are combined with an oscilloscope, on the picture screen of which a "thermal picture" of the photographed object can be directly viewed. The prismatic body forms part of the system for scanning the photographed object, and its sides are formed by or coated with mirrors. The purpose of the surrounding drum is to protect the rotating prism, but it must of course be provided with an opening through which the incoming and reflected radiation can pass. Hitherto it has been common practice to give this opening a rectangular form with two opposite sides parallel to the rotational axis of the mirror prism.

When the prismatic body rotates within a drum provided with such an opening, the air in the interstices between the inside of the drum and the sides of the prismatic body is caused to rotate along with the prismatic body, and this air current produces together with the edges of the opening and particularly that edge of the opening which meets the air current, a strong noise with a fundamental frequency dependent on the rotational speed of the prismatic body. This noise is most irritating and disturbing to the persons handling the apparatus and may also disturb the proper function of the apparatus.

SUMMARY OF THE INVENTION

It is an object of the invention to reduce this drawback. According to the invention that edge of the opening, which is passed by the sides of the rotating prism in a direction from the opening to under the wall of the drum, extends at an oblique angle to the generatrix lines of the wall of the drum. Hereby the compression of air which occurs when an edge of the prismatic body passes by the said edge of the opening, will not occur simul-

2

taneously at all points along the edge. Therefore the disturbing noise is considerably reduced.

DRAWING AND DETAILED DESCRIPTION

The invention will be described more in particular in conjunction with the accompanying drawing.

FIG. 1 shows schematically and in top view a cylindrical drum and a rotating prismatic body arranged within the drum.

FIG. 2 shows the drum with the opening in side view, the opening having a form according to one embodiment of the invention.

FIG. 3 also shows the drum in side view and illustrates another form of the opening according to the invention.

In FIG. 1 the rotating prismatic body is designated 1 and in the illustrated example the cross-section of the body has the shape of a regular hexagon. The rotational axis of the body is designated 2, and its direction of rotation is indicated by an arrow in the figure. The prismatic body rotates within a cylindrical drum 3 the wall of which is provided with an opening 4.

In the embodiment shown in FIG. 2 the opening 4 is limited by two edges 5 and 6, of which edge 5 extends along a generatrix line on the drum, i.e. parallel to the axis of the drum and the rotating body, while the limiting edge 6 according to the invention extends at an oblique angle to the generatrix lines of the wall of the drum. The edge 6 extends continuously from a point at or adjacent to one end of the drum to a point at or adjacent to the other end of the drum. The distance marked *a* in FIG. 2 is the difference between the largest and the least width of the opening 4, and in order that the best effect shall be achieved this distance should be about equal to one half of a side in the regular polygon which forms the cross section of the prismatic body 1.

In FIG. 3 that limiting edge of opening 4 which faces the rotational direction, is designated 16. In this embodiment the limiting edge has the shape of a broken, saw-tooth line, all parts of which extend at an oblique angle in relation to the generatrix of the wall of the drum. The crests and roots of the teeth may be situated on lines parallel to the axis of the drum and the prismatic body as shown in FIG. 3 but may also be situated on lines extending obliquely in relation to the generatrix lines of the drum wall. The last mentioned embodiment can be considered as a combination of the embodiments shown in FIGS. 2 and 3.

The said limiting edge may also have other forms within the scope of the invention.

I claim:

1. A device for reducing acoustic oscillations caused by the rotation of a prismatic member within a casing of substantially cylindrical form which is arranged concentrically with the rotational axis of the prismatic member, and the wall of which is provided with at least one opening arranged so that the sides of the rotating prismatic member in turn pass by the opening, characterized in that that edge of the opening, which is passed by the sides of the rotating prismatic member in the direction from the opening to under the wall of the casing, extends at an oblique angle to the generatrix lines of the wall of the casing.

2. A device as claimed in claim 1, characterized in that said edge extends continuously from a point adjacent to one end of the casing to a point adjacent to the other end of the casing.

3. A device as claimed in claim 1, characterized in that said edge is saw-tooth-shaped.

4. A device as claimed in claim 1 in which the prismatic member in a section at right angles to its rotational axis

3,477,541

3

has the form of a regular polygon, characterized in that the difference between the largest and the least width of said opening is about equal to one half of a side in said polygon.
